UNITED STATES PATENT OFFICE.

WILLIAM JAMES TOLLERTON, OF CHICAGO, ILLINOIS.

SILL CONSTRUCTION FOR CARS.

1,284,819.

Specification of Letters Patent. Patented Nov. 12, 1918.

Application filed June 11, 1915. Serial No. 33,432.

To all whom it may concern:

Be it known that I, WILLIAM JAMES TOLLERTON, a citizen of the United States, residing at Chicago, in the county of Cook and 5 State of Illinois, have invented new and useful Improvements in Sill Construction for Cars, of which the following is a full, clear, and exact description.

My invention relates to the construction 10 of railroad cars, and particularly to freight cars used for carrying grain.

The object of my invention is to make the joint or connection between the flooring and sheathing of the car so that the grain can- 15 not leak through, and so that it will not be affected by the pressure of the load within the car nor the moisture outside of the same, and will thus prevent the lower portion of the sheathing from bulging. This I 20 accomplish by the means hereinafter fully described, and as particularly pointed out in the claims.

In the drawings:

Figure 1 is a vertical sectional view 25 through the side-sill of a car and the joint of the sheathing and flooring supported thereby embodying my invention.

Fig. 2 is a perspective view of a fragment 30 of the tie-plate used in connection therewith.

Figs. 3, 4, 5, 6 and 7 are views similar to Fig. 1 each illustrating a different modification of the same.

In order to facilitate the description of 35 my invention the construction thereof illustrated in Figs. 1 and 2 of the drawings may be considered the preferred form. The modifications shown in the other figures of the drawings are all of equal value from a 40 practical standpoint.

Referring to the drawings, A represents a channel-beam car-sill, B the flooring or decking of the same, and C the sheathing thereof. The sill may be of any suitable 45 form in cross-section, and my invention applies to either the side-sills or the end-sills of the car. The flooring consists of trans- 50 verse planks and the sheathing of the usual horizontal planks. The ends of the floor planks are provided with transverse horizontal grooves b about midway between their upper and lower surfaces the depth of 55 which, preferably, exceeds the thickness of the sheathing, and the upper bifurcation or

lip d resulting from the cutting of this 55 groove b is foreshortened or cut off a distance corresponding to about one-half of the thickness of said sheathing. The lower edge of the lower plank of the sheathing is also provided with a longitudinal groove c 60 midway between its sides and the inner lip e resulting from the cutting of this groove is cut off a distance corresponding to the distance between the underside of the flooring B and the top side of groove b therein. 65

In assembling the parts of my invention, I arrange the planks of the flooring in their proper position upon the sills, substantially as shown, and then insert one edge of a tie-plate D in the grooves b as far as it will go. 70 The width of this tie-plate corresponds to the depth of grooves b or from the end of the lower bifurcation d' of said planks to the bottom of said groove, and the outer longitudinal edge thereof is bent upward to 75 form a flange E, which is of such dimensions that when the lower plank of the sheathing is properly assembled so that the outer lip f thereof rests upon sill A said flange will enter groove c, and the lower edge of the 80 inner lip e will rest upon the tie-plate. When thus assembled the flooring and tie-plate are secured to the upper flange of sill A by means of bolts g, substantially as shown, or otherwise. 85

In Fig. 3, I show a modification of my invention in which a T-beam F is substituted for tie-plate D. The web of this T is inserted in the end grooves b of the floor planks in the same manner as tie-plate D 90 does, and the upper flange thereof enters groove E in the lower edge of the lower plank of the sheathing, but the lower flange thereof projects down between the outer lip f of the sheathing and the end of the lower 95 lip d' of the flooring planks and comes in contact with the upper flange of the sill. When thus assembled the T-beam F and the flooring are secured to the upper flange of the sill A by bolts g, substantially as shown 100 in Fig. 1, or otherwise.

In Fig. 6 of the drawings, I show another modification in which the lower sheathing plank G has the outer angle of its lower edge rabbeted, and the lower lip j of the ends of 105 the floor planks extends beyond the upper lip i a distance corresponding to the thickness of the sheathing. The tie-plate I used

in this modification is the same as tie-plate D, shown in Fig. 1, but it is wider, and when inserted as far as it will go into the end grooves J in the floor planks, and the lower edge of the lower sheathing plank is seated upon the web of said tie-plate, the upwardly projecting flange k on the outer edge of the same will enter and rest in the rabbet h of the sheathing. The tie-plate and flooring 10 are secured to the upper flange of sill A by bolts K.

The modification shown in Fig. 7 of the drawings is the same as that shown in Fig. 6, excepting that a T-beam L is substituted 15 for tie-plate I, and excepting the fact that the lower flange m of said T-beam laps down in front of the foreshortened end of the lower lip n of the flooring. The outer surface of the flanges of this T-beam L is, 20 preferably, flush with the outer surfaces of the sheathing and the web of sill A, and it and the flooring are, preferably, secured to the upper flange of said sill by bolts M.

In Fig. 4 the groove a that is made in the 25 lower edge of the lowest sheathing plank is of a depth exceeding the thickness of the floor-planks, and the inner lip of said edge is cut away back from the lower edge thereof a distance corresponding to the thickness of 30 the floor-planks N so that when assembled the lower edge of the outer lip of the sheathing may rest on sill A. The upper surface of the ends of the floor-planks are depressed or rabbeted as at P, and at the inner shoulders of said rabbits the floor-planks are 35 provided with transverse grooves q. The sheathing and flooring are connected by an irregular Z-bar shaped tie-plate Q, which is seated in said rabbeted surface P and has its downwardly projecting inner flange entering grooves q in the floor-planks, and its outer upwardly projecting flange entering groove r in the sheathing. This tie-plate Q and the floor-planks are connected direct to 40 the upper flange of sill A by means of bolts r, as shown, or otherwise.

The modified construction shown in Fig. 5 of the drawing is somewhat similar to that shown in Fig. 4, except that the floor-planks 50 R are extended until their ends are flush with the outer surfaces of the sill and the sheathing. The upper surfaces s of the ends of these planks are rabbeted or depressed from their ends to a point beyond the inner surface of the sheathing, and the outer surface 55 of the lower edge of the sheathing is rabbeted as at t. A tie-plate T is interposed between the sheathing and flooring, which is substantially similar to tie-plate Q, except- 60 ing that it is wider and that its outer flange S, which enters the rabbeted surface t of the sheathing, projects upward to a greater extent than the downward projection of the other flange thereof. The inner downwardly 65 projecting flange of this tie-plate T enters

the transverse grooves v made in the floor planks at the inner shoulder of the rabbeted surfaces s thereof.

The tie-plates shown in Figs. 1 and 3 of the drawings are entirely out of sight when 70 the parts of the car are properly assembled, and the upwardly projecting outer flanges thereof, when the tie-plates and flooring are bolted or otherwise secured to the sill, not only tie the sheathing to the flooring in such 75 manner as to absolutely prevent the sheathing from buckling outward, but insure a tight joint between the same and prevent the possibility of the grain or cereals carried 80 by the car from leaking out therethrough.

Of course, it will be understood that where vertical sheathing is used in a car provided with my improvements that the upwardly projecting flange of the tie-plate (or any of the substitutions therefor to which I have referred) will enter grooves in the lower ends of said vertical sheathing planks the same as said flange would enter the groove in the lower edge of a horizontal sheathing plank, as hereinbefore described. 90 I have heretofore stated that the inner portion of the tie-plate or its equivalent is bolted or otherwise secured to the sill. This may be done or not, as desired, for it is possible in some instances not to bolt the tie-plate or equivalent member to the sill.

I do not wish to be confined to the exact proportions of the parts of my invention, as hereinbefore described, nor to the exact construction, because the principal feature, to-wit: that of making a tie-plate for accomplishing the twofold purpose of preventing leakage of grain and buckling of the sheathing and making a joint in which the said tie-plate is hidden (or blind) or partly hidden, 105 may be accomplished by modified constructions of my improvements, as hereinbefore described.

What I claim as new is:

1. In a car, the combination with sheathing planks and floor planks a portion of which latter extends under said sheathing, of a tie-plate resting upon the ends of the floor planks and having an upwardly turned flange that engages the same, a metal beam-sill having an upper horizontal flange upon which the ends of said floor-planks rest, and means for securing said tie-plate and floor-planks thereto.

2. In a car, the combination with the sheathing thereof which has a groove in its lower edge, and flooring a portion of which latter extends under said sheathing, of a tie-plate resting upon the ends of said flooring and having an upwardly turned flange that enters said groove, a metal beam-sill having an upper horizontal flange upon which the ends of said flooring rest, and means for securing said tie-plate and flooring thereto.

3. In a car, the combination with the sheathing thereof, flooring a portion of which latter extend under said sheathing, and have horizontal grooves in their ends, 5 and a metal sill upon which said ends rest, of a tie-plate, a portion of which is seated in said horizontal grooves and has an upwardly bent flange that engages said sheathing, and means for securing said tie-plate 10 and flooring to said sill.

4. In a car, the combination with the sheathing thereof which has a groove in its lower edge, flooring a portion of which latter extend under said sheathing and have 15 horizontal grooves in their ends, and a metal sill upon which said ends rest, of a tie-plate a portion of which is seated in said horizontal grooves and has an upwardly bent flange that enters said groove in the 20 lower edge of the sheathing, and means for securing said tie-plate and flooring to said sill.

5. In a car, the combination with a metal sill having an upper horizontal flange, 25 sheathing flooring the ends of which rest upon said flange, and have horizontal grooves in their ends and having the upper resulting lip foreshortened and contacting with said sheathing, a tie-plate a portion of 30 which enters said grooves and rests upon the extension of the lower lip of said ends and has an upturned flange that engages said sheathing.

6. In a car, the combination with a metal

sill having an upper horizontal flange, 35 sheathing-planks the lowermost one of which has a longitudinal groove in its lower edge, floor-planks the ends of which rest upon said flange and have horizontal grooves in their ends and having the upper resulting 40 lip foreshortened and extending under said sheathing, a tie-plate a portion of which enters said grooves and rests upon the extension of the lower lip of said ends and has an upturned flange that enters the groove in 45 said sheathing.

7. In a car, the combination with a metal sill having an upper horizontal flange, sheathing which has a longitudinal vertical 50 groove in its lower edge and has the inner resulting lip foreshortened, flooring the ends of which rest upon said flange and have horizontal grooves in said ends and the upper resulting lip thereof foreshortened and contacting with the foreshortened lip of the 55 sheathing, of a tie-plate comprising a metal beam which enters the said horizontal grooves and an upwardly flanged outer edge that enters said vertical groove, and means for securing the said tie-plate and the floor- 60 ing to said sill.

In witness whereof I have hereunto set my hand this 7th day of June, 1915.

WILLIAM JAMES TOLLERTON.
